UNITED STATES PATENT OFFICE.

FREDERIC K. PLYMPTON, OF WELLESLEY, MASSACHUSETTS.

BOTTLE CAP AND THE LIKE.

Application filed February 19, 1920. Serial No. 359,790.

To all whom it may concern:

Be it known that I, FREDERIC K. PLYMPTON, a citizen of the United States, residing at Wellesley, in the county of Norfolk, State 5 of Massachusetts, have invented a certain new and useful Improvement in Bottle Caps and the like, of which the following is a specification, reference being had therein to the accompanying drawings.

10 The object of the invention is to provide an improved closure for a milk bottle or the like of a type adapted to completely enclose and cover the mouth of the bottle or jar. In practice milk bottles and jars are commonly 15 sealed by a flat disk which is seated in the mouth of the same. This method of sealing has the objection that opportunity is presented for the collection of waste milk, water, pieces of ice and dirt in the open space above 20 the disk, so the contents of the bottle or jar are liable to be contaminated when the disk is removed, by the falling of the same into the bottle.

In order that a cap of the type contemplated by this invention may go into general use it is necessary, not only that it completely enclose and cover the neck of the bottle, but that it may be easily applied to the bottle, as well as readily removed from 30 the same without the use of special tools, and that when so removed, no part of the cap or its retaining means shall be left upon the bottle, causing additional labor at the bottling plants; and that the cap with its 35 retaining means can be manufactured and sold at a comparatively low cost. It is also desired that the cap and its retaining means be supplied to the trade in assembled form ready for application to the bottle as a single 40 unit.

A cap of metal is too expensive for common use, and consequently the cap must be made of a non metallic material, preferably of paper or pulp board, which can be easily 45 formed into the desired shape. It is necessary to provide the cap with some form of fastening means in order that the cap may not be accidentally dislodged from the bottle to which it has been applied. The 50 invention resides more particularly in novel retaining or fastening means and the combination of the same with a cap.

Referring to the drawings,

Fig. 1 is a side elevation of a cap and

its retaining means embodying the invention. 55

Fig. 2 is a view in horizontal section on line 2, 2, of Fig. 1.

Fig. 3 is a view in vertical section showing the cap and its retaining means applied to 60 the neck of a bottle and made fast thereon by crimping.

Fig. 4 is a view in horizontal section on line 4, 4, of Fig. 3.

Fig. 5 is a side elevation of a strip of retaining material showing the integral fastening projections thereof. 65

Fig. 6 is a plan view of the said strip.

Fig. 7 is a side elevation of a cap and its retaining means in crimped form ready for 70 application to a bottle.

The body 1 of the cap in Fig. 1 is formed of flexible material, preferably paper or pulp board, with the dependent flange 2, said flange being of larger diameter at the 75 bottom than at the top. Near the bottom of the flange is applied the retaining means 3, which consists of a strip of wire preferably, the ends of which are overlapped with each other when applied to the body 1, as at 80 4, Figs 1 and 7, altho it may be a continuous ring. This wire is formed with integral projections 5, 5, at intervals, as in Fig. 5, which preferably is accomplished by bending the wire to form U-shaped lateral 85 projections and closing the sides of the open portions of each U together, as in Fig. 5, so that they are parallel or approximately so.

In the process of making the cap the body 1 is moulded to give it the shape shown in 90 Figs. 1 and 7 and to press down into flattened crimps the fulness of the skirt or flange thereof, and then the retaining means 3 is applied to the skirt or flange by forcing the projections 5, 5, through the same, and is fastened thereto by bending the said projections into hook-form and clinching them at the inner surface of the skirt or material, as in Fig. 2. In making application of the retainer 3 to the skirt or flange and fastening the same thereto, the two ends of the retainer are overlapped at 4 and respectively are fastened to the skirt or flange at or beyond the point of meeting, so that the skirt or flange is held securely within the 95 ring formed by the retainer in its applied and fastened state. A short portion of one extremity, beyond the point at which the 100 105

latter is fastened to the skirt or flange, is left free to be raised and taken hold of in unfastening the cap, through disengagement of the fastening projections of such extremity from the skirt or flange, to provide for its removal.

It will be apparent that the invention provides a simple and inexpensive means of fastening a retainer to the skirt or flange 10 of a cap, and enables retainer material of commercial form to be used without waste in the manufacture of caps embodying the invention.

After the wire retainer has been fastened 15 to the skirt or flange, a preliminary crimping of the retainer, etc., as in Fig. 7, preferably is effected, so that at the time of making application of the finished cap to a bottle the final crimping by which the cap is secured 20 in place may be more easily effected, and regularity and uniformity of the crimps as in Fig. 4 may be established.

The cap is applied to a bottle and fastened in place thereon by placing it over the 25 mouth and neck of the bottle and compressing the skirt or flange and its applied retainer around the neck. The cap will be securely held in place by means of the compressed retainer.

30 In some cases, the unattached finger-hold portion of one end of the strip constituting a retainer may be folded back upon itself as at 6, Fig. 5, or otherwise be so formed that it can be grasped by one's fingers without 35 slippage in the operation of removing the cap from the bottle to which it has been applied.

To remove the cap, the finger-hold portion is grasped and by pulling outwardly 40 thereon the strip of wire is easily pulled from the skirt or flange, which will allow the cap to be lifted from the bottle. The strip can be entirely detached in this operation, or only loosened sufficiently to permit 45 the cap to be removed.

It is desired by the trade that it shall be impossible to remove a cap of the general 50 type including, my own, and replace the same after the contents of the bottle have been tampered with, without detection. The invention aims to meet this requirement by so forming the retaining means and fastening the cap to the bottle that the removal of

the cap shall so damage it that it cannot be again resealed upon the bottle, although it 55 may be used for a temporary cover.

It will be seen that the complete cap can be simply and inexpensively manufactured as a complete unit in automatic machinery.

I claim:

1. A bottle or jar cap comprising a flanged body of flexible material having combined with its depending flange a non-continuous fastening ring having overlapping end-portions fastened to the said flange at or beyond the point of meeting, one of such end-portions being adapted to be used as a handle in disengaging the fastenings of such end-portion for loosening the cap from the bottle or jar to which it has been applied. 70

2. A bottle or jar cap comprising a flanged body of flexible material having combined with its depending flange a non-continuous ring having integral fastening hooks constituted by U-shaped projections formed at intermediate points in the ring, with the open portion of the U closed together and the sides thereof approximately parallel to each other. 75

3. A bottle or jar cap comprising a flanged cap of flexible material having combined with its depending flange a non-continuous ring with overlapping ends, fastened to the flange by integral U-shaped projections 85 formed at intermediate points in the strip of material of which the ring is made, with the side portions of the U closed together, and with said projections extending through the material of the flange and clinched. 90

4. A bottle or jar cap comprising a flanged cap of flexible non-metallic material having combined with its depending flange a metal ring fastened thereto by means of integral retaining hooks constituted by U-shaped projections formed at intermediate points of said ring and having their sides closed together and approximately parallel, with the projections extending through the material of the flange and the ends thereof clinched. 100

In testimony whereof I affix my signature in presence of two witnesses.

FREDERIC K. PLYMPTON.
